US0D1082194S

(12) **United States Design Patent** (10) **Patent No.:** **US D1,082,194 S**
(45) **Date of Patent:** **** Jul. 1, 2025**

(54) **MODULAR CLEANING PAD**

(71) Applicant: **Scrub Daddy, Inc.**, Pennsauken, NJ (US)

(72) Inventors: **John O'Brien**, Cherry Hill, NJ (US); **Perrin L. Bauder**, Philadelphia, PA (US)

(73) Assignee: **Scrub Daddy, Inc.**, Pennsauken, NJ (US)

(**) Term: **15 Years**

(21) Appl. No.: **29/915,073**

(22) Filed: **Oct. 25, 2023**

(51) LOC (15) Cl. **07-05**

(52) U.S. Cl.

USPC **D32/40**

(58) **Field of Classification Search**

USPC D4/137; D8/90; D28/7; D30/158;

D32/15, 17, 25, 35, 40

CPC A45D 2200/1009; A45D 2200/1018; A47K 7/02; A47L 13/10; A47L 13/16; B60S 3/045
